UNITED STATES PATENT OFFICE.

WALTER E. BENNETT AND EDWARD P. MERWIN, OF BOSTON, MASSACHUSETTS, ASSIGNORS TO THE MORLEY SEWING MACHINE COMPANY, OF SAME PLACE.

MACHINE FOR SEWING BUTTONS TO FABRICS.

SPECIFICATION forming part of Letters Patent No. 359,956, dated March 22, 1887.

Application filed June 12, 1885. Serial No. 168,475. (No model.) Patented in England July 10, 1884, No. 9,985; in France July 21, 1884, No. 163,411, and in Belgium July 22, 1884, No. 65,842.

To all whom it may concern:

Be it known that we, WALTER E. BENNETT and EDWARD P. MERWIN, citizens of the United States, residing at Boston, in the county of 5 Suffolk and State of Massachusetts, have invented new and useful Improvements in Machines for Sewing Buttons to Fabrics, (which invention was patented in England July 10, 1884, No. 9,985; in France July 21, 1884, No. 10 163,411, and in Belgium July 22, 1884, No. 65,842,) of which the following is a specification.

This invention relates to improvements in machines for sewing buttons to fabrics, and is 15 in the nature of an improvement upon the Patent No. 265,532, of October 3, 1882, to which reference may be had, the object being to improve the construction of the button turning and clamping mechanism for operating 20 said button turning and clamping devices, the manner of hanging and controlling the action of the swinging needle-bar frame, to provide improved means for cutting the thread near the needle, improved stitch-forming mechanism to co-operate with that shown in said patent, whereby four threads, instead of two, as heretofore, are passed through the shank of 25 the button, and improved clutch devices to co-operate with the needle-bar frame and thread-cutter, whereby said frame is brought to a stop at the proper position for said cutter to act.

In the drawings forming part of this specification, Figure 1 is a side elevation of a machine for sewing buttons to fabrics, partly in section and with the side plates removed, embodying our improvements. Fig. 2 is a face view of the devices which operate the button turning and clamping devices. Fig. 3 is a 35 view, partly in section, of the button-clamping devices. Fig. 4 is a section on line $x-x$, Fig. 1. Fig. 5 is an end view of the clutch devices, the wheel having one side broken off. Figs. 6 and 7 are respectively side and end 40 elevations of the front end of the machine below and including the presser-foot. Fig. 8 is an under side plan view of the presser-foot, showing thereon the looper devices and the

shaft and devices which operate the latter. Fig. 9 is a bottom plan view. Fig. 10 is a top 50 plan view of the end plate. Fig. 11 is an end elevation of the swinging needle-bar frame, the needle-bars, cast-off, and back-up, and showing sections of the shaft on which the needle-bar swings and their arms which actuate it, together with the lever which regulates the motion of the needle-bar, a side view of the thread-cutter, and the improved devices 55 on the needle-bar by which the needle-feed is adjusted. Fig. 12 is a side elevation of the 60 swinging needle-bar frame and the parts thereto attached, an end view of the thread-cutter being there shown. Fig. 13 is a perspective view of a portion of the lower end 65 of the button-trough, showing a button at the lower end thereof in the position in which it is held previous to dropping it between the button-clamping devices, and also the latter-named devices beneath the end of said trough holding a button in position to let the needle 70 pass through its shank, and illustrating the operative positions of the two needles during their first movements to make the stitch whereby the button is sewed to the fabric. Fig. 14 is a perspective view of the under side 75 of the presser-foot, illustrating in connection therewith the ends of the needles and the cast-off in the act of forming the improved stitch. Fig. 15 is a side elevation of that part 80 of the button clamping and turning devices adjoining the delivery end of the button-trough, showing a part of the button-turning shaft and the clamp-shank therein in section, and a part of the piston which operates said clamp.

In the drawings, A is the frame of the machine. B is the button-hopper, into which the buttons are placed, as in said patent. D is the button-trough, having the cap 12 on its side near its delivery end, and the button-turner 90 10 and actuating devices, rod 9, lever r, and cam d on shaft e, also substantially as shown in said patent, whereby the buttons are moved, controlled, and delivered to the improved button clamping and turning devices, as herein- 95 after set forth. The said button-turning mech-

anism consists of a hollow shaft, 13, (see Figs. 1, 3, 13, and 15,) hung in suitable bearings in frame A, and extending substantially from the rear end of the machine to the front end thereof, passing between the delivering end of the button-trough D and the upper side of the presser-foot 17. The rear end of the said hollow shaft 13 has a pinion, 8, thereon, with which the end of a lever, K, engages, the latter having thereon a geared segment, as shown. Lever K is pivoted on the stud 7 at the rear end of the machine, and is given a suitable vibratory motion by the engagement of its lower end with a cam-groove in the inner face of the wheel f on the end of the shaft c, whereby shaft 13 is given a properly-timed reciprocating rotary motion. A cover, K', (shown in section in Fig. 1,) is secured over said lever and pinion. A lever, m, is pivoted on cover K', one end of which engages with a cam, 6, on the side of the wheel f, whereby lever m is given a vibratory motion.

The end of the shaft 13, which carries the button-clamping devices, is shown in section, together with the latter in detail in Figs. 3 and 4, and is further illustrated in Figs. 13 and 15.

The shaft 13 has inserted therein the piston n, whose rear end projects through the end of said shaft opposite the end of said lever m, and is by said lever given an endwise reciprocating motion, and its opposite end enters the hollow shank 21 of the button-clamp 19. The latter-named end of piston n is screw-threaded and has a nut, 22, thereon, which engages with the end of shank 21, when the piston is, by the motion of lever m, moved toward said shank, and thereby the button-clamp is moved from the abutment 18. Spring 20, Fig. 3, acts to move the clamp against said abutment and hold the button therebetween. Said nut 22 on the piston serves to adjust the degree of movement of the button-clamp from the abutment 18. A cap, 14, is screwed on the end of said shaft, holding said spring in place. Shaft 13 is properly slotted to allow of the movement of the clamp 19 to and fro relative to the abutment 18.

By reference to Figs. 1 and 13 it will be seen that the segment of a circle formed by the borders of the clamp 19 and abutment 18, when the latter are not separated to let a button drop between them, act with their borders very near the end of the button-trough D, and thus they prevent any buttons escaping from the latter, excepting when the clamp 19 and the abutment 18, which is secured on shaft 13, are turned by the rotation of shaft 13 to bring that portion of the said abutment in which is the slot 60 under the end of trough D to permit the shank of the button to enter said slot, as shown in Fig. 13, and when the said clamp moves from the abutment, as below described, to let the button drop between the latter and the clamp, the latter then turns to the position shown in Fig. 13, and holds the shank of the button in a horizontal plane, whereby the eyed needle 37 is permitted to

pass up through said shank after passing through the fabric which lies on the presser-foot. The feed motion of the needle 37, after the button is attached to the fabric, slides the latter along, and causes the button to be drawn from between the button-clamp 19 and the abutment 18.

The operation of the shaft 13 is properly timed, actuated by the connection of wheel f with the shaft c, which is geared to the main shaft b to cause it to rotate to carry a button over so that the needle can enter its shank, as shown in Fig. 13, and, as described in said patent, as often as one is required, and the movement of the button-clamp is timed to that of the shaft 13.

The needle-bar frame s is substantially the same as that shown in said patent, and carries, as does the latter, the needle-bars t² and t³, on which are secured, respectively, the eyed and hook needles 37 and 38, and also the cast-off bar t and the back-up bar t⁴, all operating, substantially as in said patent, through their connection with the shafts b and c. In this construction, however, the needle-bar frame is hung on a shaft, 31, (see Figs. 9, 11, and 12,) in the frame of the machine, and oscillates thereon. Said oscillating motion in one direction results from the action of cam c² on shaft c against a roller hung in the pivoted block 43, which block is hung on a screw-stud, 50, in the frame A of the machine, (see Figs. 6 and 7,) and the motion of frame s in the opposite direction results from the action of a cam, 39, hung on shaft b, against one arm of the elbow-lever 40, having roller 41 thereon, on shaft 31, whose other arm extends up by the side of frame s and has a screw, 42, therein, by which the contact of said arm with the frame s is regulated. By the employment of the cam 39 and lever 40, (with means for regulating the latter, as described,) instead of a spring, as heretofore, for swinging the frame s in one direction, a positive motion of the frame is obtained, which conduces to regularity of action in sewing, and the shock resulting from the action of a spring is avoided.

A further improvement in the devices connected with the swinging frame is provided by the aforesaid block 43, which is pivoted on frame A, opposite the cam c², and hangs between the latter and the vertically-adjustable block 44, operated by the screw 45, located in projecting arms on the needle-bar frame s. By moving the block 44 toward and from the pivot 50 of the block 43 the extent of the swing of frame s is adjusted, and consequently the length of stitch desired is obtained, since the feed of the machine is by the needles.

The thread-cutter 18 is in the form of an elbow-lever having a thumb-piece on the end of its long or horizontal arm, and its cutting-edge at the extremity of its short arm is pivoted on the frame of the machine in front of the eyed needle 37, and in such position that when the latter swings to a rest before feeding, the side of said needle is in the line of movement of

said cutting-point of knife 18, so that when the latter is operated said cutting-point engages a part of the thread which needle 37 carries and cuts the latter, clearing the work from the 5 needle, so that it may be removed from the machine, and leaving thread enough in the needle for continuing the work. A suitable retracting-spring is attached to the knife to keep its point swung away from the needle, as shown to in Fig. 11. Said cutter obviates taking up a tool for doing this work and drawing out any extra thread before beginning to sew again.

The principal sewing devices of this machine are adapted to produce a stitch like that 15 made by the devices described in said patent, and described and shown in Letters Patent No. 236,350, of 1881, and No. 257,047, of 1882; but to improve said stitch and make it substantially a lock-stitch the improved looper mechanism, hereinafter described, is combined with the sewing devices of this machine. By the machines referred to in said patents a stitch is made in the fabric previous to sewing one 20 through the shank of the button. Then the fabric is fed along, and the stitch is taken through said shank, said first stitch preventing the button-stitch from slipping; but said looper devices, by which two loop-strokes are made in the same place in the fabric, obviate the necessity of making said first stitch, and the 25 stitching is begun directly through the button-shank, so that no stitch is shown on the right side of the work, except that through said shank.

To provide for making two loop-strokes in the same place, as aforesaid, it is desirable to carry the thread of the first loop or stitch across under the fabric, above the point of the hook-needle, so that the latter, when it moves 35 upward to form the second stitch, will pass through the loop so drawn across, and therefore the looper 28 is hung under the presser-foot 17, between the plate 30 and the latter, a pin, 29, on the looper engaging in a curved 40 slot in plate 30, as shown in Figs. 8 and 13, the first of said figures showing different positions of the looper in dotted lines, and Fig. 13 showing the position of the looper after having 45 caught the thread held by the eyed needle 37 and so spread it as to permit the hooked needle 50 which holds the prior loop to carry the latter over said thread and thence through the fabric.

The looper 28 is provided with a hook-shaped point, as shown, to engage with said 55 loop or thread. Its rear end is pivoted to the end of an arm, 27, and the latter is fixed on the end of a reciprocally-rotating vertical shaft, y , which extends from the lower part of the machine through the hollow presser-foot 60 bar 15 to a point just under the presser-foot, the latter having a split sleeve, 16, thereon slipping over the end of said bar, and secured on the latter by a screw, as shown. The said vertical shaft is rotated by the lever w , (see 65 Fig. 9,) which is pivoted to the machine at 51, and is given a vibratory motion in a horizontal plane by the cam v , a stud in said lever en-

gaging in a suitable groove in the latter. Lever w has on its free end a geared segment, w' , which engages with a pinion, y' , on the lower 70 end of said looper-shaft y .

The operation of the looper 28 with the sewing devices to make the improved stitch above referred to is as follows: The eyed needle 37 goes up through the shank of the button. The 75 hook-needle 38 then catches the loop and draws it down through the fabric. The looper-hook then engages with the thread leading from the fabric to the eyed needle and carries it across over the hook-needle, and the eyed needle, 80 which has meanwhile gone down, rises again, carrying a new loop up within the first one, the new loop being seized by the hook-needle, as was the first one, and drawn down. Thus four threads are carried through the button- 85 shank and locked to the fabric, so that any strain on the button will not cause them to slip, and the button is much more firmly attached to the fabric than heretofore. The combined action of the arm 27 on shaft y and 90 the engagement of the pin 29 with the curved slot in the plate 30 give to the looper-point its requisite movements transversely under the presser-foot.

The presser-foot 17 is given its requisite reciprocating motions by suitable connection with one of the above-mentioned shafts of the machine, and a spring, 23, Figs. 1 and 6, located on the presser-bar 15, the latter being supported on the inner side of the end plate, 100 A', a top plan view of which is shown in Fig. 10. Machines of this class are usually run by power instead of by a treadle, and to provide convenient means for drawing down the presser-foot, to insert and remove work by a foot-treadle, so that the hands of the operator may be free, a shaft, 24, is hung across the inner 105 face of said end plate, on one end of which is an arm, 25, extending over and having a bearing on a block secured on the presser-bar, and on the opposite end of said shaft is a crank-arm and pin, 34 and 26, a chain or other suitable connection with the latter providing means for attaching a treadle thereto.

The proper operation of the needle-bar 115 frame s , whereby when the machine is stopped the needles are invariably brought to rest at a given position, thus bringing them into operative nearness to the cutter 18, and at a proper commencing-point for sewing, is secured by 120 the combination with the driving-shaft b and the auxiliary shaft c of clutch devices, as hereinafter described, operating with a driving-wheel, E , in combination with a foot-treadle, whereby when the latter is released 125 the clutch between the shaft b and wheel E is disengaged and the former is stopped at a given point in its rotation.

The wheel E has a clutch-pin, a , on its inner side, and rotates freely and continuously on 130 the end of shaft b , by any suitable belt applied thereto. A collar, 3, is secured to shaft b , adjoining the inner side of wheel E , by a pin, 4, which passes through the collar and shaft,

and the ends of which project beyond the sides of the former, and have loosely hung thereon the latch *h*, which naturally swings toward the wheel *E* and in the track of the clutch-pin *a*. A lever, *F*, is pivoted by the side of the wheel, as shown, and a foot-treadle is connected with its end by a hook-and-wire connection, and a suitable coil or other spring is connected to said wire and a fixed part of the machine, whereby the end of lever *F* is lifted up and its upper thin edge is against the inner side of the latch *h*, as in Fig. 1, holding the latter away from pin *a* and stopping the machine; but when the operator would start the machine he bears upon said foot-treadle, (and continues to do so while he wishes the machine to run,) drawing lever *F* away from the latch *h*, and leaving it free to engage with pin *a*. Thus it is seen that the shaft *b* is always stopped with the pin and the latch in the relative positions shown in Fig. 1, and consequently the devices on shafts *b* and *c*, controlling the movements of the needle-bar frame *s*, invariably leave the needles in the same position when the machine is stopped.

The elbow-lever *e*, hung on the cross shaft 32 and engaging with the cam *d* on shaft *c*, operates the needle and cast-off bars *t*² and *t* through connection therewith by the pitman *j*.

The lever *r*, which operates the parts 9 and 10 on the button-trough *D*, is hung also on said cross-shaft 32, a stud, 33, thereon also engaging in one of the slots in cam *d*.

The shaft *i*⁴, Fig. 9, has an arm, *i*, with a stud thereon engaging with a part of cam *d*, and to the opposite end of said shaft is connected the take-up *i*². The needle-bar *t*², carrying the eyed needle, is operated by mechanism substantially as described in said Letters Patent of 1882.

What we claim as our invention is--

1. In a machine for sewing shank-buttons to fabrics, the hollow shaft 13, the piston *m*, having the nut 22 thereon, the abutment 18, the clamp 19, having shank 21, the spring 20, and mechanism, substantially as described, for giving said shaft a reciprocating rotary motion and for imparting to said piston a longitudinal reciprocating motion, combined and operating substantially as described. 50

2. The block 43, pivoted to the frame of the machine, the feed-adjusting block 44, supported on screw 45 on the needle-bar frame *s*, cam *c*², and means, substantially as described, for rotating the latter, combined and operating substantially as described. 55

3. The combination, with the swinging needle-bar frame *s*, carrying the needle 37, of the knife 18, pivoted on the machine to have its cutting-point swing near said needle, and clutch mechanism, substantially as described, operating in connection with the needle-bar-frame driving devices, whereby said needle is stopped at a position near said knife, substantially as set forth. 60

4. The needles 37 and 38, the presser-foot 17, the looper 28, having pin 29 thereon, the slotted plate 30, shaft *y*, having arm 27 thereon, and mechanism, substantially as described, for operating said needles and for imparting a reciprocating rotary motion to the shaft *y*, combined and operating substantially as set forth. 70
